FURNITURE WEB SUSPENSION PLATE

Otto L. Kramer, Los Angeles, Calif.

Application September 24, 1935, Serial No. 41,892

17 Claims. (Cl. 24—194)

My invention relates generally to the seats of chairs and like articles of furniture and more particularly to a connection and suspension plate for the strips of webbing that are positioned in the seat frame.

The principal objects of my invention are, to generally improve upon and simplify the construction of the webbing attaching and suspension means and to provide a web attaching and suspending device that is highly effective in securely holding the webbing that is connected to the device so that it cannot possibly sag as a result of slipping through the suspension means.

A further object of my invention is, to provide a furniture web suspension that will effectively secure the ends of sections of webbing of predetermined and uniform lengths, thus producing a structure of uniform tension and balanced resiliency so that the applied weights and strains are uniformly distributed throughout the entire webbed structure and transmitted through the attaching means to the frame that surrounds the webbing.

A further object of my invention is, to provide a web suspension comprising two cooperating plates of metal or the like which when properly assembled, effectively clamp the webbing that is applied to the plates and one of said plates carrying a pointed projection that passes through the center of the engaged webbing to materially assist in securing the same to the plates and said pointed projection having an aperture that coincides with an aperture in the other plate to provide a point of connection for one end of the helical spring that connects the web engaging plates with the seat frame of the furniture.

A further object of my invention is, to provide a furniture web suspension that may be easily and quickly applied to the web and likewise easily and quickly connected by the helical springs to the furniture seat frame.

With the foregoing and other objects in view my invention consists in certain novel features of construction and arrangements of parts that will be hereinafter more fully described and claimed and illustrated in the accompanying drawing in which:

Figs. 1 and 2 are perspective views of the cooperating plates that are applied to the strips of webbing.

Fig. 3 is a plan view of the end of a piece of webbing with the plates applied thereto and also showing said plates connected to a seat frame by a helical spring and a member that is driven into the frame.

Fig. 4 is a vertical section taken on the line 4—4 of Fig. 3.

Fig. 5 is a plan view of a modified form of the suspension plate.

Fig. 6 is a cross-section taken on the line 6—6 of Fig. 5, and showing the position of the web that passes through the slots in said plate.

Referring by numerals to the accompanying drawing which illustrates a preferred embodiment of my invention, 10 designates a substantially rectangular plate of metal provided with a longitudinally disposed slot or opening 11.

That portion of the edge of the metal at the side of the slot or opening that is adjacent the center of the plate is bent downwardly to provide an inclined lip or flange 12.

Formed through the plate 10, between the side of the opening that is provided with the flange 12 and the adjacent edge of said plate, is a longitudinally disposed slot 13.

Formed through that portion of plate 10 on the opposite side of the portion that is provided with slot 13, are apertures 14, one of which is located midway between the ends of the plate.

The cooperating web engaging plate is illustrated in Fig. 2 and this member comprises a narrow plate 15 of metal, the length of which is practically the same as plate 10.

The material along one edge of plate 15 is bent downwardly at right angles to form a depending lip or flange 16 and the ends thereof terminate inwardly from the ends of plate 15 in order that said lip or flange 16 may readily project downwardly through the opening 11.

Formed integral with the edge of plate 15, opposite the depending lip or flange 16, is an outwardly projecting pointed prong 17 that is shaped somewhat similar to a spear head and said prong occupies a plane slightly below the plane occupied by the plate 15. This arrangement is necessary in order to permit the prong to lie immediately beneath the plate 10 when plate 15 is applied thereto and the two plates are engaged on the webbing.

Formed through the prong 17 is an aperture 18, which when the two plates are properly assembled, coincides with the central one of the apertures 14 in plate 10.

In applying the cooperating attaching and suspension plates to a strip of webbing such as W, a portion of said webbing at the end thereof, is folded double and said doubled end is inserted from the top downwardly through slot 13 and the end of the folded portion is then brought upwardly from the bottom through opening 11.

Plate 15 is now inserted lengthwise through that portion of the folded webbing that projects upwardly through opening 11 and when said plate is positioned so that its ends project equidistant from the edges of the webbing, the prong 17 is forced through the center of the webbing at the fold line thereof.

Thus plate 15 is positioned between the two layers of the folded portion of the webbing with 10 the prong projecting from the folded end of the webbing.

Plate 15 with the webbing passing therearound is then turned slightly and the projecting prong 17 is moved downwardly through opening 11 until 15 the ends of plate 15, beyond flange 16, overlie the ends of plate 10, beyond the ends of opening 11.

Plate 15 is now slightly rotated so as to position the prong 17 immediately beneath that portion of the plate 10 in which the central one of the 20 apertures 14 is formed, thus aligning the said central aperture with the aperture 18 and when so positioned the ends of plate 15 beyond flange 16, overlie the ends of plate 10 and depending flange 16 occupies a position immediately adjacent and parallel with the inclined flange 12.

The body of the webbing beyond the plates is now pulled away from said plates, thereby pulling plate 15 so that depending flange 16 moves toward 30 inclined plate 12 to firmly grip the interposed portion of the webbing and the end of a conventional helical spring S is now inserted through the central one of the apertures 14 and the aperture 18 in prong 17.

The outer end of the helical spring is engaged 35 in an aperture that is formed in a prong shaped plate 19, the latter being driven into the seat frame.

Formed in the sides of the prong 19, are notches 20 and after the prong has been driven into the 40 seat frame, it is anchored therein by means of nails 21 that are driven downwardly through the frame member and through the notches 20 (see Fig. 3).

Thus when the webbing and cooperating plates 45 are properly assembled, the doubled end of the webbing passes through slot 13 and around plate 15 with one thickness of the webbing effectively clamped between the depending flange 16 on plate 15 and the inclined flange 12 on plate 10.

Inasmuch as furniture webbing is generally 50 loosely woven, the prong 17 may be passed through the webbing without breaking the yarn or cords from which it is woven and thus the webbing is very securely attached to the cooperating plates and slack or sag in the webbing due to slipping or tearing is effectively prevented.

Inasmuch as the prong 17 underlies a portion 55 of plate 10, a double thickness of metal is provided for the attachment of the helical spring and such construction produces double strength and security at the point of greatest strains and friction between the webbed structure and the seat frame.

The prong on the plate or bar 15 may be inserted 60 through the webbing at predetermined points and as the doubled portions of the web are folded over the plate, said plate with the prong projecting through the webbing, may be threaded through the slots 13 and 12 and positioned on top of plate 10 directly over slot 11 so that the depending flange 16 on plate 15 cooperates with flange or lip 12 on plate 10 in gripping and securing the webbing to the cooperating plates.

The advantage of this construction is to enable 75 the plates to be applied to the web at predeter-

mined lengths so as to produce the desired tension and to make it possible to follow prescribed patterns in making a multiplicity of foundations for a known type of furniture frame.

In Figs. 5 and 6 I have shown a modified construction wherein a plate 22 is provided with three parallel slots 23, 24 and 25 with a lip or flange 26 depending along one edge of the intermediate slot 24.

Where such a plate is used, the webbing is 10 threaded downwardly through slot 25, thence beneath flange 26 and upwardly through slot 24, thence downwardly through slot 23, thence beneath that portion of the webbing below flange 26 and thence upwardly through slot 25 underneath the overlying portion of the web that passes downwardly through said last mentioned slot. 15 This construction involves only one plate and may be advantageously employed for firmly securing the webbing to the seat frames of certain 20 types of furniture.

Thus it will be seen that I have provided a furniture web connection and suspension that is relatively simple in construction, inexpensive of manufacture, easily and quickly applied to the webbing and effectively holding the latter against strains and stresses that would otherwise result in sagging and slipping of the webbing.

It will be understood that minor changes in the 30 size, form, and construction of the various parts of my improved furniture web suspension may be made and substituted for those herein shown and described without departing from the spirit of the invention, the scope of which is set forth in 35 the appended claims.

I claim as my invention:

1. In a furniture web suspension, a pair of co-operating web receiving plates, one of which is provided with slots for the reception of the doubled end of the web, a flange depending from the slotted plate along one edge of one of the slots therein and a flange depending from one edge of the other plate, which flange occupies a position adjacent and parallel with the flange on the other plate when the two plates are assembled.

2. In a furniture web suspension, a pair of co-operating web receiving plates, one of which is provided with slots for the reception of the doubled end of the web, a flange depending from the slotted plate along one edge of one of the slots therein, a flange depending from one edge of the other plate, which flange occupies a position adjacent and parallel with the flange on the other plate when the two plates are assembled and a prong projecting from the edge of the plate having the flange depending from its edge.

3. In a furniture web suspension, a pair of co-operating web receiving plates, one of which is provided with slots for the reception of the doubled end of the web, a flange depending from the slotted plate along one edge of one of the slots therein, a flange depending from one edge of the other plate, which flange occupies a position adjacent and parallel with the flange on the other plate when the two plates are assembled, a prong projecting from the edge of the plate having the flange depending from its edge and said prong and the plate that is provided with the slots being provided with apertures that coincide when the plates are applied to the end of a strip of webbing.

4. In a furniture web suspension, a plate provided with a pair of slots for the reception of a strip of webbing, a flange depending from said plate along one edge of one of the slots therein, a second plate adapted to overlie one of the slots

in the first mentioned plate and a flange depending from one edge of the second mentioned plate, which flange occupies a position adjacent and parallel with the flange on the first mentioned plate when the two plates are properly assembled.

5. In a furniture web suspension, a plate provided with a pair of slots for the reception of a strip of webbing, a flange depending from said plate along one edge of one of the slots therein, 10 a second plate adapted to overlie one of the slots in the first mentioned plate, a flange depending from one edge of the second mentioned plate, which flange occupies a position adjacent and parallel with the flange on the first mentioned plate when the two plates are properly assembled 15 and a prong projecting from said second mentioned plates and adapted to overlie a portion of said first mentioned plate.

6. In a furniture web suspension, a plate provided with a pair of slots for the reception of a strip of webbing, a flange depending from said plate along one edge of one of the slots therein, 20 a second plate adapted to overlie one of the slots in the first mentioned plate, a flange depending from one edge of the second mentioned plate, which flange occupies a position adjacent and parallel with the flange on the first mentioned plate when the two plates are properly assembled, 25 a prong projecting from said second mentioned plates and adapted to overlie a portion of said first mentioned plate and said prong and said first mentioned plate being provided with apertures that register with each other when the two plates are properly assembled.

30 7. In a furniture web suspension, a plate provided with a pair of slots, a flange depending from said plate along one edge of one of the slots therein, a narrow plate adapted to overlie the first mentioned plate, a flange depending from one 35 edge of the narrow plate and a prong projecting from the other edge of said narrow plate.

8. In a furniture web suspension, a plate provided with a pair of slots, a flange depending from said plate along one edge of one of the flanges 40 therein, a narrow plate adapted to overlie the first mentioned plate, a flange depending from one edge of the narrow plate, a prong projecting from the other edge of said narrow plate and said prong and said first mentioned plate being provided with apertures that coincide when the plates 45 are properly assembled.

9. In a furniture web suspension, a plate slotted for the reception of the doubled end portion of a strip of webbing, a narrow plate adapted 50 to be inserted through the doubled end of the strip of webbing and a prong projecting from one edge of said second mentioned plate.

10. In a furniture web suspension, a plate slotted for the reception of the doubled end portion 55 of a strip of webbing, a narrow plate adapted to be inserted through the doubled end of the strip of webbing, a prong projecting from one edge of said second mentioned plate and which prong and first mentioned plate are provided 60 with apertures that coincide when the plates are properly assembled.

11. In a furniture web suspension, a plate slotted for the reception of the doubled end portion

of a strip of webbing, a narrow plate adapted to be inserted through the doubled end of the strip of webbing, a prong projecting from one edge of said second mentioned plate and cooperating web engaging flanges depending from both plates.

5

12. In a furniture web suspension, a plate slotted for the reception of the doubled end portion of a strip of webbing, a narrow plate adapted to be inserted through the doubled end of the strip of webbing, a prong projecting from one 10 edge of said second mentioned plate, which prong and first mentioned plate are provided with apertures that coincide when the plates are properly assembled and cooperating web engaging flanges depending from both plates.

15

13. In a furniture web suspension, a plate provided with three slots and a flange depending from the plate along one edge of the intermediate slot.

14. In a furniture web suspension, the combination with a plate provided with three slots and a flange depending from said plate along the intermediate one of said slots, of a plate adapted to overlie the first mentioned plate and a flange depending from one edge of said second 25 mentioned plate and adapted to cooperate with the flange on the first mentioned plate in gripping an interposed web.

15. In a furniture web suspension, the combination with a plate provided with three slots 30 and a flange depending from said plate along the intermediate one of said slots, of a plate adapted to overlie the first mentioned plate, a flange depending from one edge of said second mentioned plate and adapted to cooperate with the flange 35 on the first mentioned plate in gripping an interposed web and a prong projecting from said second mentioned plate and adapted to pass through the web that is engaged by said plates.

16. In a furniture web suspension, the combination with a plate provided with three slots and a flange depending from said plate along the intermediate one of said slots, of a plate adapted to overlie the first mentioned plate, a flange depending from one edge of said second mentioned 40 plate and adapted to cooperate with the flange on the first mentioned plate in gripping an interposed web, a prong projecting from said second mentioned plate and adapted to pass through the web that is engaged by said plates and said first 45 mentioned plate and said prong having apertures that coincide when the two plates are assembled and applied to a section of webbing.

17. In a furniture web suspension, the combination with a plate provided with three slots 50 and a flange depending from said plate along one edge of the intermediate slot, of a web threaded through one of the slots and extending upwardly through the intermediate slot beneath the flange that depends from the side thereof, thence downwardly through the third slot, thence beneath that portion of the web that underlies the flange and thence upwardly through the first mentioned slot beneath that portion of the webbing that passes downwardly through 55 said first mentioned slot.
